(57) **CLAIM**

I claim the ornamental design for the vehicle expansion dock,
as shown and described.

DESCRIPTION

FIG. 1 is a perspective view of a vehicle expansion dock
showing the new design.

FIG. 2 is a top view of the vehicle expansion dock.

FIG. 3 is a front view of the vehicle expansion dock.

FIG. 4 is a right side view of the vehicle expansion dock.

FIG. 5 is a left side view of the vehicle expansion dock.

FIG. 6 is a bottom view of the vehicle expansion dock.

FIG. 7 is a back view of the vehicle expansion dock; and,

FIG. 8 is perspective view of the vehicle expansion dock
showing a preferred environment of the vehicle expansion
dock.

The broken lines in FIGS. 2 and 4-8 are for environmental
purposes only and form no part of the claimed design.
